(57) **CLAIM**

The ornamental design for a chair.

DESCRIPTION

FIG. 1 is a perspective view of a chair showing my new design.

FIG. 2 is a left side elevational view thereof. The right side elevational view is a mirror image of the left side;

FIG. 3 is a front elevational view thereof.

FIG. 4 is a rear elevational view thereof.

FIG. 5 is a perspective view thereof.

FIG. 6 is a top plan view thereof.

FIG. 7 is a bottom plan view thereof.

FIG. 8 is a perspective view thereof.

FIG. 9 is a perspective view thereof.

FIG. 10 is a perspective view thereof.

FIG. 11 is a perspective view thereof.

FIG. 12 is a perspective view thereof; and,

FIG. 13 is a perspective view thereof.

The dashed lines shown on the seat and backrest of the chair are for illustrative purposes only and form no part of the claimed design.
